SEWING MACHINE NEEDLE AND CUTTER PLATE

Zacharia Routtenberg, Los Angeles, Calif.

Application June 20, 1932. Serial No. 618,164

2 Claims. (Cl. 112—129)

This invention relates to improvements in the removable plate that serves to cooperate with the needle and the cutter of a sewing machine.

One of the objects of this invention is to provide a simplified plate that can easily be substituted for the standard plate in a sewing machine.

Another object is to make the needle and cutter plate of two portions, of which the one is designed to be replaced for different cutting operations.

Other objects will appear from the following description and appended claims as well as from the accompanying drawing, in which:

Fig. 1 is a top plan view of the larger portion or section of the improved needle and cutter-plate.

Fig. 2 is a top plan view of the smaller exchangeable section having a cut-out for the cutter for narrow cutting operations.

Fig. 3 is a cross-section on line 3—3 of Fig. 1.

Fig. 4 is a top plan view of the smaller cutter plate section of a slightly modified form for wider cutting operations.

Fig. 5 is a cross-section on line 5—5 of Fig. 4.

Fig. 6 is a cross-section on line 6—6 of Fig. 2.

Fig. 7 is a longitudinal-section on line 7—7 of Fig. 4.

The larger plate-section illustrated in Fig. 1 is always used together with a smaller plate-section such as illustrated in either of Fig. 2 or Fig. 4, the needle of a sewing machine naturally having to remain in the same operative position regardless of cutter operations on account of other mechanisms normally arranged below the needle-plate for the second thread to cooperate with the thread in the needle. For this reason the needle-hole 7 is provided in this larger section together with the aperture 8 for the material shifter. This larger section is therefore also provided with the portion 9 having a top surface 10, to be in a level of the customary needle plate, over which the material handled in a sewing machine moves in the direction of the arrow 11. Parallel to the arrow 11, an edge or shoulder 12 is indicated in

Fig. 1 as the lateral termination of this topmost portion 9. Two wings 13 extend sidewise from the portion 9 beyond this shoulder 12 suitably spaced below the top surface 10.

This space above the surface 14 of the wings 13 and below the surface 10 of the portion 9, clearly illustrated in Fig. 3 serves to take care of the thickness of the smaller removable cutter plate-section illustrated in Figs. 2, 4, 5 and 6. Every cutter section is provided with a thicker center portion 15 and thinner side portions 16

offset by the shoulders 17, the shoulders 17 to abut against the shoulder 17_a of the wings 13 of the larger plate-section, and the top surface 10_a of the smaller section to come flush with the top surface 10 of the larger section. 60

For narrow cuts, the lateral edge 12 serves as a cutting edge to cooperate with the cutter 18 of which a portion is indicated in Fig. 3 sidewise of the needle 19, the smaller section illustrated in Fig. 2 having for this purpose a cut-out 20 to 65 allow a passing of the cutter below the surface 10_a of this smaller plate-section.

Inasmuch as cloth is cut at various distances sidewise along the stitching produced by a needle of a sewing machine, a cutting edge is provided 70 at various distances from the lateral edge 12 of the larger plate-section by means of the exchangeable plate-sections.

In Figs. 4 and 5 one modified form of smaller plate-section is illustrated with a recess 21 forming a cutting edge 22 to cooperate with the modified form of cutter indicated at 18_a, the inclined recess portion 23 merely facilitating a cleaning of the cutter recess 22. 75

It must be understood that a cutter normally 80 operates a shorter distance than the needle of a sewing machine, in fact, only from a point closely above the cloth or material handled in the sewing machine to a point just below the top surface of the combined needle and cutter-plate, explaining that a mere recess, such as indicated at 22 is fully sufficient to take care of the movements of the cutter while the needle normally has to move a greater distance below the needle-plate for intertwining the threads. 85 90

Having thus only shown two forms of cutter plate-sections, the section illustrated in Fig. 2 for narrower cuts and the section illustrated in Fig. 4 for wider cuts, it must be understood that any number of exchangeable cutter plate-sections can be provided for various widths of cutting, all being very much similar to the illustration of Fig. 4 excepting for the width between the cutting edges 22 and the front edge 24 of this smaller cutting section. 95 100

The front edge 24 is intended to abut against the shoulder 12 of the larger plate-section illustrated in Fig. 1. The smaller plate-sections can therefore be shifted back and forth between the wings 13 of the larger plate-section with respect 105 to the shoulders 17 and 17_a until the front edge 24 abuts against the shoulder 12 of the larger plate-section, the smaller plate-section being held in position by screws or pins for which holes have been indicated at 25. 110

Having thus described my invention, I claim:—

1. A combined needle and cutter-plate comprising a larger section and a smaller exchangeable section, the larger section having a portion forming the top over which the material is handled with a needle-hole and a feeder-hole and being shouldered along a line parallel to the movement of the material handled over the plate forming an abutment edge, the larger section having furthermore two wings extending laterally from the said portion beyond the said edge and set off below the said top, the smaller section having a heavier portion with shoulders to fit shiftably between said wings and having portions to rest upon said wings with a top to come flush with the top of the first named section and with a lateral edge to abut against the first named edge, the smaller section having furthermore a recess forming a cutting edge parallel to the other edges.

2. A combined needle and cutter-plate comprising a larger section and a smaller exchangeable section, the larger section having a portion forming the top over which material is handled with a needle-hole and a feeder-hole and being shouldered along a line parallel to the movement of the material handled over the plate forming an abutment and cutting edge, the larger section having furthermore two wings extending laterally from said portion beyond said edge and set off below said top, the smaller section having a heavier portion with shoulders to fit shiftably between said wings and having portions to rest upon said wings with a common top to come flush with the top of the first-named section, the smaller section having furthermore a recess in its top to leave the cutting edge free in the combined tops.

ZACHARIA ROUTTENBERG.
